ADJUSTABLE CLOSET STORAGE AND HANGING RACK

Claude M. Hales, 3506 Preston Ave., Durham, N.C.

Filed Feb. 19, 1965, Ser. No. 83,904

Term of patent 14 years

(Cl. D33—8)

I claim:

The ornamental design for an adjustable closet storage and hanging rack, substantially as shown.
